UNITED STATES PATENT OFFICE.

EDWARD TELLESON, OF BINGHAMTON, NEW YORK.

SYRINGE-TANK.

1,092,231.

Specification of Letters Patent.

Patented Apr. 7, 1914.

Application filed September 29, 1911. Serial No. 652,012.

To all whom it may concern:

Be it known that I, EDWARD TELLESON, a citizen of the United States, residing at Binghamton, in the county of Broome and 5 State of New York, have invented certain new and useful Improvements in Syringe-Tanks, of which the following is a specification.

My invention relates to syringe tanks in 10 which a fabric covered metallic body adapted to be filled with liquid has a nozzle connection with a fountain syringe tube and it has for its object a light cheap portable tank for holding liquid, adapted to be hung 15 on the wall or placed against the body, and for having a tubular connection with a syringe and for applying the liquid to the body for body use and application.

With these objects in view my invention 20 consists in certain novel features of construction and arrangement of parts as will be hereinafter fully described and pointed out in the claim, reference being had to the accompanying drawings, in which—

25 Figure 1 is a front view partly in section of my device. Fig. 2 is a perspective view of a part of my device. Fig. 3 is a side view of my device. Fig. 4 is a perspective view of a modified form of my device.

30 The same reference characters denote like parts in each of the several figures of the drawings.

In carrying out my invention I provide a body portion A preferably in the form of a 35 disk or oblate spheroid, as shown in Figs. 1 and 3, in the top of which I have inserted an opening or mouth B provided with the stopper C. In the lower body portion of A I provide the outlet tube D adapted to receive over the end of it a rubber syringe 40 tube E, which outlet has upon it the nozzle F. Over the body portion A I place a fabric cover G for a general cover to the body. To further add to the flexible nature of the

covering, I have placed about it the felt 45 covering H. On the body portion A I mount the hanger I.

This invention is designed to overcome serious defects and objections existing in fountain syringes in general use, one of 50 which is that the present constructions are not easily supported for the purpose of filling and emptying and the other being that the bag of the syringe becomes weak 55 from the pressure of the water, resulting in the tearing of the seams and rendering the syringe practically worthless. By reason of my construction a handy means is provided for suspending the syringe and a band 60 passes around the syringe and forms a strengthening or reinforce for the bag at exactly the location where the pressure of the water results in tearing the seam. Thus 65 my improvements overcome these defects and insure a more desirable article of this character and greatly increase the wear or life of the syringe.

Having thus described my invention what I claim as new and for which I desire Letters Patent, is as follows:

70

The fountain syringe herein shown and described consisting of a metal body having a large filling spout and a small outlet, a nozzle fitting in said outlet, a fabric covering over the entire body, a band passing 75 centrally around the body and projecting therefrom to form a protector for said body and an arm retained between the body and band and having at its upper end an opening for hanging the syringe in a vertical 80 position.

In testimony whereof I have affixed my signature, in presence of two witnesses.

EDWARD TELLESON.
